UNITED STATES PATENT OFFICE.

TONJES AUGUST CARL BOTH, OF NEW YORK, N. Y., ASSIGNEE, BY MESME ASSIGNMENTS, TO RALPH A. SCHOENBERG, OF BRANCHPORT, NEW JERSEY.

ELECTRIC SWITCH.

1,172,923.

Specification of Letters Patent. Patented Feb. 22, 1916.

Original application filed July 9, 1910, Serial No. 571,196. Divided and this application filed September 16, 1910. Serial No. 582,332.

To all whom it may concern:

Be it known that I, TONJES AUGUST CARL BOTH, a citizen of the United States, and a resident of New York, in the county 5 of New York and State of New York, have invented certain new and useful Improvements in Electric Switches, of which the following is a specification, taken in connection with the accompanying drawings, 10 which form a part of the same.

This invention relates to electric switches and more particularly to push button switches, and is a divisional application of my parent application for mechanical 15 movement filed July 9, 1910, Serial No. 571,196.

In the accompanying drawings showing illustrative embodiments of my invention, and in which the same reference numerals 20 refer to similar parts in the several figures, Figure 1 is a vertical section through my electric switch used as a push button switch and in which the receptacle is formed of two complementary and preferably insulating members; Fig. 2 is a horizontal section substantially on the line 2, 2 of Fig. 1; Fig. 3 is a vertical section substantially on line 3—3 of Fig. 2; Fig. 4 is a transverse vertical section substantially on the line 30 4—4 of Fig. 1, a portion of the mechanism being shown partly in side elevation for the purpose of better illustration; Figs. 5 and 6 are perspective views of details used in the construction shown in Figs. 1 to 4; Fig. 7 is a detail perspective view of an insulating axle or arbor used in the construction shown in Figs. 1 to 4 inclusive; Fig. 8 is a detail perspective view of the preferred 35 form of ears which I preferably use with the two piece receptacle; Fig. 9 is a detail perspective view of the cartridge; Fig. 10 is a perspective view of the locking levers; Fig. 11 is a fragmentary perspective view of the locking levers showing one means of 40 connecting the locking levers together.

In my present invention I use an insulating receptacle 1 formed of two members or halves 2, 2 which are complements of each other. This receptacle is usually made 45 out of porcelain and to permit the easy drawing of the different portions of the receptacles from the molds I preferably, though not necessarily, make the two members or halves 2, 2 identical, so that when

they are placed together their meeting surfaces would be on the line 3, Fig. 4, entirely inclosing the opening 4 within which the electric switch is mounted.

The switch movement in this form of my invention is very similar to that shown in my said parent application, but it differs materially in the manner of mounting the axle or arbor, the driving and driven members and in the axle or arbor itself, which, in this form of my invention, is formed of some insulating material such as porcelain. This insulating axle or arbor 5, Fig. 7, is provided at either end with trunnions 6, 6 and with a non-circular portion 7, 7, both of which are preferably, but not necessarily, formed integral with the insulating axle or arbor 5. It is also provided with a longitudinal groove 8 for a purpose to be hereinafter described.

The insulating axle or arbor 5 is mounted 5 in a cartridge 9, Fig. 4, which is very similar to the cartridge 87 shown in Fig. 16 of my said companion or parent application; the trunnions 6, 6 are loosely mounted in apertures 10, 10, cast or otherwise formed, 20 within the respective halves or other complementary members 2, 2, Fig. 4. This cartridge is secured to the receptacle 1 by any suitable means such as by the screws 11, Fig. 4. In this form of my invention the driving member 12 is formed of substantially two rings 13, 13 connected together by means of a connecting plate 14; one of the rings 13 is provided with slotted lugs 15, 15 to which are attached the stems 16 and 17 of the push buttons 18 and 19, respectively, Fig. 1. This driving member 12 is mounted on the insulating axle or arbor 5 by passing the same through the rings 13, 13. I also preferably provide the driven member 20 with two rings 21, 21, each ring being preferably provided with an inwardly extending tongue 22, 22 to fit within the groove 8 in the insulating axle or arbor 5, it, of course, being understood that the rings 21 surround the axle or arbor 5. This arrangement of the tongues 22 and groove 8 is one means for preventing relative rotation between the driven member 20 and the insulating axle or arbor 5, though other means may be used, if desired.

Around the insulating axle or arbor I arrange the resilient member of any approved

form, such for example as a coil spring 23 having ends 24 and 25, Fig. 4, which lie on opposite sides of the driven member 20 and the connecting plate 14 of the driving member 12.

5 In the bottom of the cartridge 9 I mount the opposed locking levers 27 and 36, the former being provided with the engaging surface or tooth 26 and the latter with the 10 similar engaging tooth 52. Both levers 27 and 36 are normally pressed upward by means of the coil or other spring 59 engaging with a depending lug 53, the same in all respects as in my companion and parent 15 case Serial No. 571,196. The two locking levers 27 and 36 are preferably secured together in any suitable manner to permit their independent rocking movement and yet to insure that the depression of one of 20 the levers will also depress the other. I have found in practice that one manner of so securing them is to form an opening 55 in one of the levers such for instance as 36 and form a tongue 56 on the other lever 27, 25 having its end 57 pass through the opening 55 in the lever 36 and be bent down as shown in Fig. 11 so that both levers 27 and 36 will be pivotally and loosely connected together. While I preferably use two locking levers 30 such as 27 and 36, I may in some cases use only one such locking lever which would then temporarily lock the driven member 35 from movement in one direction.

Downward pressure upon the push button 18, Fig. 1, will be transmitted to the slotted ears 15 of the driving member 12 and will cause the connecting plate 14 of the driving member to move the end 25 of the coil spring 23 away from the end 24 of 40 the spring which will be held in the position shown in Fig. 1 by engaging with the driven member 20 which is held in the position shown in Fig. 1 by means of the tooth 26 upon the lever 27. The energy will be 45 continued to be stored up in the spring 23 until the end 28 of the stem 16 contacts with the end 29 of the lever 27 when this lever will be depressed and the tooth 26 freed from the driven member 20, permitting the 50 driven member to snap over into its opposite position. The driven member 20 will then be held by the other locking tooth 52 on the second locking lever 36 until the other push button 18 has stored up energy in the 55 spring 23 and its stem 60 engages the end 61 of the lever 36 and depresses both levers releasing the locking tooth 52 from engagement with the driven member 20 when the driven member, with its axle and movable 60 contacts, will fly over or snap into its opposite position.

In the present construction where the axle or arbor 5 is of insulating material it is not necessary to insulate the movable contact 30 65 from it and from the base or receptacle 1.

On the contrary it is merely necessary to secure the movable contact to the insulating arbor. One such means which I have illustrated by way of example is to provide the movable contact 30 with some non-circular 70 opening, which is preferably formed square to snugly fit over the square portion 7 of the axle or arbor 5, see Figs. 3 and 4. As I have also shown this construction as a double pole push button switch, I use preferably two 75 such movable contacts 30 and mount them at either end of the insulated arbor or axle 5 by simply sliding them upon the squared portions 7, 7 after the parts of the switch movement have been assembled in the cartridge and then locate the trunnions 6, 6 within their respective apertures 10, 10 which securely and economically hold the 80 movable contacts 30, 30.

The arms 31 and 31 of the movable contact 30 are preferably bifurcated to receive between them the fixed contacts 32 and 33 carried by the binding posts 34 and 35, the same being in all respects similar to those shown in my parent co-pending applica- 85 90 95 100 105 110 115 120 125 130

In the operation of this construction, the driven member positively moves with the axle or arbor 5 due to the fact that the tongues 22 are mounted within the groove 8 as previously noted. By this arrangement when the locking levers 27 or 36, as the case may be, are released, the torsion of the spring 23 is transmitted to the axle or arbor 10, through the tongues 22 and groove 8, and consequently this insulating axle or arbor 5 has a limited rocking movement within the recesses or apertures 10, 10 in the members 2, 2, this rocking movement of course being transmitted to the moving contacts 30, 30 to cause them to quickly make or break connection with the fixed contacts 32, and 33, as the case may be; thereby insuring in this device as well as in all the others a quick make of the current, as well as a quick break of it without arcing.

The two halves or members 2, 2 are quickly assembled and held together after the insertion of the electric switch by any suitable means. I have found in practice that a very quick and efficient method of securing the two members together is by a plurality of transverse screws 37 and 38, arranged preferably in different horizontal planes and extending in from opposite sides of the receptacle 1, Fig. 2. By the aid of these same screws or securing members to fasten the two halves 2, 2 together, I also secure ears 39, Fig. 8, to which a face plate 40, or other element may be secured by means of the screws 41, Fig. 1. These ears consist preferably, though it is to be understood that their shape may be varied without departing from my invention, of a body member 42, a flange 43 bent at substantially 130

right angles to the body 42, said flange having a laterally extending member 44 provided with screw threaded apertures 45, 45 for the reception of the screws 41, Fig. 1. 5 The stems 42 of the ears are preferably located in cut-out or rabbeted portions 46, 46 in the upper portion of the members 2, 2, see Figs. 1 and 2. The body member 42 is then secured to one of the members 2 by one 10 of the screws; for example screw 37 taking into the upper screw threaded aperture 47 in the stem 42. A similar screw 38 is then passed through the other member 2, which will require it being mounted upon the opposite side of the receptacle 1 from that which the screw 37 has been inserted. This 15 second screw 38 is also inserted in a different horizontal plane, which for example is shown beneath the screw 37 and, as indicated 20 in dotted lines in Fig. 2, will take into the lower screw threaded aperture 48, Fig. 8 of the ear 39. A similar ear 39 is secured on the opposite side of the receptacle 1 in the same manner, Figs. 1 and 2. It will 25 therefore be seen that the same securing mechanism for securing the ear 39 to the receptacle will also simultaneously perform the double purpose of securing the two sections 2, 2 to each other, thereby saving expense 30 in the cost of manufacture including a saving in the number of parts and the cost of labor in assembling them.

To guide the push buttons 18 and 19 I arrange preferably semi-circular concave 35 bearings 49 and 49 in each of the side members 2, Fig. 2. In addition thereto I may, though not necessarily, place guide slots 50, 50 in each member 2, 2 to coöperate with guiding lugs 51, 51 located on the push buttons 18 and 19, or any other suitable guiding means may be used, if desired.

It will be seen that in all forms of my invention a very short leverage is required to permit the teeth 26 and 52 to escape from 40 the driven member and consequently I can make my switch very shallow which is of marked commercial advantage if the switch is to be used either as a push button molding switch, or used with the aid of a bridge

piece, as a push button flush switch, it of course being understood that the different forms of my invention shown can all be converted from a molding push button switch to a flush push button switch. In this invention I also preferably avoid 55 securing the movable contact by means of either rivets or split washers, or other similar mechanical expedients, for the movable contacts are preferably simply slipped over the non-circular or square portions 7, 7 60 of the insulating axle 5.

Having thus described this invention in connection with an illustrative embodiment thereof to the details of which I do not desire to be limited, what is claimed as new 65 and what it is desired to secure by Letters Patent is set forth in the appended claims:

1. In an electric switch the combination of a driving member; a driven member reciprocated by the driving member; a pivoted lever to temporarily lock the driven member against movement in one direction; and a second pivoted lever to temporarily lock the driven member against movement in the other direction, said levers being rockable 75 independently of each other but each being depressed when the other is depressed.

2. An electric switch consisting of a hollow closed receptacle formed of complementary insulating portions; an axle of insulating material rotatably mounted on said portions and held by them against axial movement; a fixed contact member; a movable contact member having a non-circular portion in engagement with a non-circular portion of said axle so as to be rotated with the latter; a driving member mounted to rotate on said axle but free to rotate with relation thereto; a driven member actuated by the driving member and actuating the axle to 90 move the movable contact; and locking means to temporarily lock the driven member.

TONJES AUGUST CARL BOTH.
